STANDING-VALVE LIFTER.

Application filed June 6, 1927. Serial No. 196,764.

In pumping deep wells such as oil wells, the standing valve rests on a tapered seat and becomes thoroughly fixed in this seat due to the weight of the fluid, sand, and various other causes. When it is desired to remove the standing valve, suitable means are provided whereby the plunger engages the valve which is then pulled out by pulling on the sucker rods. Due to the fact that the standing valve is securely fastened in its seat, a severe strain is placed on the sucker rods which tends to stretch them and so materially weaken the various rods that they will break, either at the time of pulling or later during the pumping operations and this results in a tedious fishing job.

An object of our invention is to provide a novel means of lifting the standing valve from its seat so that it may be readily removed.

Still another object is to provide a standing valve lifter which may be used in conjunction with any well-known type of standing valve puller and which is operated by the rotation of the sucker rods.

A further object is to provide a standing valve lifter which is simple in construction and effective in operation.

Other objects, advantages, and features of invention may appear from the accompanying drawing, the subjoined detailed description, and the appended claims.

In the drawing:

Fig. 1 is a longitudinal sectional view of the well tubing with our lifter in position therein.

Fig. 2 is a longitudinal sectional view of our lifter.

Fig. 3 is a sectional view taken on line 3, 40 of Fig. 2.

Referring more particularly to the drawing:

The well tubing 1 has depending from the bottom thereof a tube 2 on the bottom of which tube is provided a shoe 3 in which the standing valve 4 is seated. It is evident that the tubing 1 may extend down to the shoe 3, or the shoe may be entirely dispensed with and the bottom of the tubing suitably tapered to provide a seat for the standing valve. This construction is all well-known and usual in the industry.

The standing valve 4 is of usual and well-known construction and a rod 5 is secured to the top thereof. The rod 5 is threaded into the lower end of a guide 6, which guide is

square in cross-section, the purpose of which will be further described. A cage 7 rests on a shoulder 8 in the tubing, which shoulder may be the top of the tube 2, or it may be 60 formed directly within the tubing 1.

A threaded post 9 extends into the guide 6 and a square block 10 is threaded to receive the post 9, said block being slidable in the guide 6. The post 9 is formed with a puller 11 on the top thereof, which puller may be a pair of fingers, as shown, or a threaded pin, or any other suitable type such as are well-known and in common use.

A flange 12 is formed on the post 9 and the cage 7 is mounted between the puller 11 and flange 12, said cage being freely rotatable on the post. A nut 13 on the bottom of the post 9 prevents the block 10 from screwing off of said post. The rod 5 is bored, as at 14, in the top thereof, and bleed holes 15 extend into the bore so that water, sand, and so forth, can drain from the guide 6.

In operation the rod 5 is tightly screwed onto the standing valve 4 and the guide 6 is tightly screwed onto the rod, thus the guide, rod, and standing valve are non-rotatably held since the standing valve is tightly seated in the shoe 3. The plunger 16 is provided with suitable means, such as the bayonet joint 80 17 for engaging the puller 11. The plunger is lowered to engage the puller when it is desired to remove the standing valve and is then rotated, screwing the post 9 into the block 10, and thus causing the block to move upwardly on the post pulling the standing valve from its seat, after which the plunger and puller assembly are all removed from the well without any strain on the rods.

When the standing valve 4 is returned into the hole and it is necessary to get off of the puller 11 with the plunger 16, the standing valve must be held against rotation. For this purpose we provide lugs 18 on the lower end of the standing valve 4, which lugs engage 95 projections 19 on the inside of the shoe 3, thus holding the standing valve against rotation. Of course, after the valve has been in use for a considerable length of time it will be thoroughly seated and the lugs 18 are of no value, except during the time that the standing valve is first being placed in position.

Having described our invention, we claim:

1. In a well including a standing valve and a plunger, puller means on the plunger, a cage seated in the well tubing, a threaded post extending through said cage, means on said

- post adapted to be engaged by said puller means, and means secured to said standing valve and to said post whereby the standing valve is lifted when said post is rotated.
5. 2. In a well including a standing valve and a plunger, puller means on the plunger, a cage seated in the well tubing, a threaded post extending through said cage, a guide secured to the standing valve, a block non-rotatably held in said guide, said post being threaded through said block, and coupling means on said post adapted to be engaged by said puller means whereby said post may be rotated to lift the standing valve.
10. 3. In a well including a standing valve and a plunger, a cage seated in the well tubing, a threaded rod rotatably mounted in the cage, puller means on the plunger, means on said rod adapted to be engaged by the puller means, a guide secured to the standing valve, a block non-rotatably and slidably mounted in said guide, said post being threaded through the block whereby the standing valve is lifted on rotation of said post.
15. 4. In a well including a standing valve and a plunger, puller means on the plunger, a cage seated in the well tubing, a threaded post extending through said cage, means on said post adapted to be engaged by said puller means, and means secured to said standing valve and to said post whereby the standing valve is lifted when said post is rotated, and
- means non-rotatably holding said standing valve when seated in the well.
35. 5. In a well including a standing valve and a plunger, puller means on the plunger, a cage seated in the well tubing, a threaded post extending through said cage, means on said post adapted to be engaged by said puller means, and means secured to said standing valve and to said post whereby the standing valve is lifted when said post is rotated, and means non-rotatably holding said standing valve when seated in the well, said holding means for the standing valve including lugs projecting from the standing valve, and projections on the seat adapted to be engaged by said lugs to hold the standing valve against rotation.
40. 6. In a well including a plunger, a standing valve seated therein, a rod secured to said standing valve, a guide secured to said rod, a cage seated in the well tubing, a threaded post rotatably mounted in the cage and depending therefrom, a block non-rotatably held in said guide through which said rod is threaded, puller means on the plunger, and means on the rod adapted to be engaged by said puller means whereby said rod is rotated to lift the standing valve.
45. 60. In testimony whereof, we affix our signatures.

ORVAL M. TURNER.
JOSEPH J. STEPHENS.
